US0D1035920S

(12) **United States Design Patent** (10) **Patent No.:** **US D1,035,920 S**
(45) **Date of Patent:** **** Jul. 16, 2024**

(54) **FRAME AND INFILL PANEL**

(71) Applicant: **Bott GmbH & Co. KG**, Gaildorf (DE)

(72) Inventors: **Bernd Geiger**, Gaildorf (DE); **Jürgen Dahner**, Gaildorf (DE); **Simon Dunkinson**, Bude (GB); **Witalij Breimeier**, Schwaebisch Hall-Hessental (DE)

(73) Assignee: **BOTT GMBH & CO. KG**, Gaildorf (DE)

(**) Term: **15 Years**

(21) Appl. No.: **29/810,471**

(22) Filed: **Oct. 5, 2021**

(30) **Foreign Application Priority Data**

May 18, 2021 (EM) 008544621

(51) **LOC (14) Cl.** **25-02**

(52) **U.S. Cl.**

USPC **D25/60**
